UNITED STATES PATENT OFFICE

WATSON KEDERIS AND BENJAMIN M. ELFRETH, OF MERCHANTVILLE, NEW JERSEY

SUPPORT FOR PORTABLE FIRE EXTINGUISHERS

Application filed April 19, 1928. Serial No. 271,343.

This invention relates to improvements in holding devices for fire extinguishers.

The primary object of this invention is the provision of an efficient bracket or holder for hand operated fire extinguishers, embodying means which will efficiently receive fire extinguishers so that the same can be removed therefrom only by a vertical upward movement; the improved holder or bracket embodying an economical assemblage of parts which efficiently mount the fire extinguisher so that the handle thereof cannot be operated except upon detachment of the fire extinguisher.

A further and important object of this invention is the provision of an improved holding device for hand operated fire extinguishers or the like comprising pressed metal parts having means for supporting the fire extinguisher along a side thereof, at the top and bottom of the fire extinguisher.

Other objects and advantages of this invention will be apparent during the course of the following detailed description.

In the accompanying drawings, forming a part of this specification, and wherein similar reference characters designate corresponding parts throughout the several views,

Figure 1 is a side elevation of the preferred embodiment of the improved holder for fire extinguishers, showing a wall attaching bracket type of holder with novel details therein, and novel means associated with the fire extinguisher for cooperation therewith.

Figure 2 is a top plan view of the fire extinguisher and its bracket details.

Figure 3 is a rear elevation of the bracket or holder showing the fire extinguisher in place.

Figure 4 is a sectional view taken substantially on the line 4—4 of Figure 3.

Figure 5 is a front elevation of the fire extinguisher attached portion of the holder or bracket construction.

Figure 6 is a plan view of the details of Figure 5.

Figure 7 is a side elevation showing a modified form of holder for attaching the improved fire extinguisher to a steering post or other column.

Figure 8 is a side elevation of the bracket shown in Figure 7.

Figure 9 is a front elevation of the bracket of Figure 8.

Figure 10 is a plan view of the bracket of Figure 8.

Figure 11 is a sectional view taken substantially on the line 11—11 of Figure 8.

Figure 12 is a fragmentary plan view showing a modified construction of supporting lugs permanently secured on the fire extinguisher body in a different relation than that illustrated in Figures 1 and 7 of the drawings.

Figure 13 is a fragmentary front elevation of the detail of Figure 12.

In the drawings, wherein for the purpose of illustration are shown preferred and modified embodiments of the invention, the letter A may generally designate the improved fire extinguisher holding construction, which may consist of a bracket B attachable in a stationary relation to a wall C or the like. A fire extinguisher body attaching means D is provided for cooperation with the bracket B in support of the fire extinguisher E. If desired, a modified form of bracket B' may be provided for attaching to a steering column F or the like, and in lieu of the means D special permanently secured bracket engaging lugs G may be provided upon the fire extinguisher E, as shown in Figures 12 and 13 of the drawings.

Referring to the bracket B, the same may be formed of pressed steel metal, preferably including the vertically elongated plate 15, having laterally bulged enlargements 17 and 18 at the lower and upper ends thereof, with a handle engaging arm attaching shank 19 extending from the top thereof. The body 15 is peripherally provided with a rearwardly extending flange 20, adapted to space the body normally from the attaching surface C to which it is connected. Above and below each of the enlargements 17 and 18 it is preferred to provide openings 22 adapted to receive screws, nails, or the like, by means of which the bracket may be attached to the support C.

In each of the enlargements 17 and 18, it

is preferred to provide tapered dove-tailed female sockets, preferably constructed by stamping flanges 24 and 25 from the bracket plate 15, and bending the same transverse to the front surface of the plate 15. The flanges 24 and 25 are connected along straight juncture lines with the plate 15, which diverge downwardly, as shown in Figure 3 of the drawings, so that the sockets or openings 26 between the flanges 24 and 25 taper with a decreasing width downwardly. The flanges 24 and 25 are bent in a transverse converging relation from the plate 15 to the free edges thereof, as shown in Figure 4, so that the sockets 26 in addition to tapering with a decreasing width downwardly, increases in width from the front edges of the flanges 24 and 25 to the plate 15, as can be seen from Figure 4 of the drawings. This provides a dove-tail socket having a tapered width thru the height thereof. These flanges 24 and 25 are of course provided on each of the enlargements 17 and 18 of the bracket plate, so that upper and lower dove-tailed sockets are provided on the bracket B with the upper ends thereof open, and adapted to receive the tapered lugs 30 and 31 respectively of the means D to be subsequently described.

A holding arm 35 is provided for the handle 36 of the fire extinguisher, to hold the same inoperative. This arm 35 includes an upwardly extending substantially S-shaped body portion 36^a, having the lower end thereof provided with laterally extending flanges 37 which are riveted at 38 to the front face of the shank 19 of the attaching bracket B, as shown in Figure 1. The plane of the body 36^a extends normal to the plane of the bracket B, and the arm body 36^a extends above the top edge of the bracket plate 15, as shown in Figure 1. At its free end the arm 35 is provided with substantially L-shaped lateral extensions 39 at opposite sides of the body 36^a, as shown in Figures 1 and 3 of the drawings, and present horizontal front surfaces disposed in a plane forwardly of the plane of the bracket plate 15, and adapted to engage the T-shaped handle 36 of the fire extinguisher E, as shown in Figures 1 and 7 of the drawings, to hold the handle normally inoperative during support of the fire extinguisher upon the improved bracket construction.

The fire extinguisher E is of the usual type, having a cylindrical shaped casing body 40, from the upper wall of which the T-shaped handle 36 extends.

Referring to the portion D of the bracket construction which is attachable to the extinguisher casing 40, for cooperation with the wall supported bracket B, the same preferably includes an elongated body strip 45, the upper and lower ends of which may be enlarged and provided with the lugs 30 and 31 thereon for detachable reception in the dove-

tailed sockets of the bracket B. At the upper and lower ends the divergent attaching flanges 46 are provided, transversely apertured, and adapted to receive attaching bolts 47 therethrough. A split band 48 is adapted for cooperation with these attaching lugs 46 at the upper and lower ends of the bracket B, the ends of each split band 48 being flanged at 49 and apertured for receiving the bolts 47 in the relation illustrated in Figure 6 of the drawings. The lugs 30 and 31 have side walls 51 and 52 which converge downwardly from the upper edges thereof to the lower edges thereof, and diverge from their attachment with the strip or body 45 outwardly to the front plate 52^a which connects the same. Thus, the lugs 30 and 31 are formed to fit into the upper and lower sockets of the bracket B, with a dove-tailed connection.

As to the application of the bracket D upon the fire extinguisher casing 40, the bands 48 are clamped about the casing 40, and it is preferred that the casing 40 have spaced annular beads 60 thereabout, to receive the bands 48 therebetween, as shown in Figure 1, to hold the same in place. The bolts 47 may be adjusted to clamp the bands tightly about the casing 40, and it is to be noted that the lugs 30 and 31 thus project transversely from a side of the casing 40.

As to the application of the fire extinguisher upon the bracket B, it is merely necessary to place the lugs 30 and 31 at the open upper ends above the female sockets provided on the bracket B, and move the extinguisher E downwardly until the lugs 30 and 31 are seated in the sockets of the bracket B. The lugs are then held in the sockets so as to prevent dropping of the fire extinguisher E or the pulling of the same away from the bracket B in a right angled relation therewith, it being necessary to lift the extinguisher E in a vertical direction, or an upward direction along the bracket B to effect detachment therefrom. It is to be noted that when the lugs 30 and 31 are in their sockets of the bracket B the handle 36 at its upper T-shaped end engages against the angle pieces 39 of the arm 35, to hold the handle 36 inoperative.

With the modified form of bracket B', the same reference characters as above given for the form of bracket B apply to the similar parts which appear in the bracket B', so far as applicable. The bracket B' distinguishes over the bracket B in that the plate or strip 15' thereof at the upper and lower ends thereof is provided with clamping bands 70, having adjusting bolts 71 for drawing the ends thereof together. The strip body 15' is of course provided with the upper and lower sets of flanges 24' and 25', preferably struck integral therewith, which converge forwardly and downwardly to provide the dove-tailed sockets 26' in the same nature and for the same reason as the sockets 26 of the form

of bracket B above described. The handle engaging arm 35' is mounted in the same relation at the top of the support 15', as the arm 35 for the form of invention B, and for the same reason.

The bracket B' is clamped upon the post or column F by means of the split bands 70, as shown in Figure 7 of the drawings, and this positions the sockets 26' to receive the lugs 30 and 31 of the extinguisher casing clamping bracket D above described.

In lieu of providing the special casing bracket D, the lugs G may be welded or permanently secured as a part of the casing 40 of the extinguisher E, as shown in Figures 12 and 13 of the drawings. These lugs G are preferably stamped of sheet metal, comprising the side walls 80 and 81 having a connecting front wall 82. The side walls 80 and 81 converge transverse to the wall 82 and away therefrom, and also converge downwardly along the wall 82, as shown in Figures 12 and 13 of the drawings, and it is preferred that along the edges of the flanges 80 and 81, remote from the wall 82, the same are outwardly flanged at 85, which may be welded, riveted, or otherwise secured in any approved manner to the walls of the casing of the fire extinguisher, as shown in Figures 12 and 13.

From the foregoing description of this invention it is apparent that a novel bracket structure for supporting hand operated fire extinguishers has been provided, which may be economically manufactured in a compact relationship of parts, for efficiently supporting a fire extinguisher in an inoperative position, where the same may be readily grasped and detached merely by an upward and outward pull. Vibration and settling tend to dispose the fire extinguisher in a more secured and efficient bracket supported relation upon the wall or column attached bracket.

Various changes in the shape, size, and arrangement of parts may be made to the forms of invention herein shown and described, without departing from the spirit of the invention or the scope of the claims.

We claim:

- 50 1. In a supporting device for portable fire extinguishers and the like the combination of a support, a plurality of vertically spaced extensions along the support providing upwardly and forwardly opening tapered sockets, a holder above said extensions for the handle of the fire extinguisher, and lugs for attachment with the fire extinguisher having a shape for a dove-tailed detachable support in the said sockets.
- 60 2. In a bracket construction for fire extinguishers a supporting bracket having a plurality of tapered sockets open at the top and at the front thereof, a fire extinguisher casing, lugs on the fire extinguisher casing for snug detachable conforming fitting in said

sockets, said lugs having detachable means for fixedly connecting the same on said casing.

3. In a holder for portable fire extinguishers the combination of a bracket having vertically spaced sockets therein, a fire extinguisher casing having spaced annular beads thereabout, a body having vertically spaced lugs rigid thereon for detachable fitting in said sockets, and clamping band means contractibly carried by said body for clamping about the casing between said beads, to rigidly support said lugs on the casing in laterally projecting relation therefrom.

4. As an article of manufacture a fire extinguisher bracket of sheet metal construction comprising a supporting body having a pair of flanges struck therefrom in a downwardly convergent spaced relation longitudinally of the body and in an outwardly extending convergent relation transverse to the body.

5. In a holding device for supporting portable receptacles the combination of a bracket having socket portions thereon, a receptacle, a lug shaped for a dove-tailed fitting in said socket, and contractible band arms connected with the lug at the opposite sides thereof for rigidly connecting the lug on the receptacle in a radially extending relation therefrom.
